CHESTER L. HILL, OF LANCASTER, PENNSYLVANIA, ASSIGNOR TO UNITED STATES ASBESTOS COMPANY, OF MANHEIM, PENNSYLVANIA, A CORPORATION OF PENNSYLVANIA.

PACKING AND PROCESS OF MAKING THE SAME.

1,168,807.

Specification of Letters Patent. Patented Jan. 18, 1916.

Application filed February 20, 1915. Serial No. 9,538.

To all whom it may concern:

Be it known that I, CHESTER L. HILL, a citizen of the United States, residing at Lancaster, in the county of Lancaster and State of Pennsylvania, have invented certain new and useful Improvements in Packing and Processes of Making the Same; and I do hereby declare the following to be a full, clear, and exact description of the invention, such as will enable others skilled in the art to which it appertains to make and use the same.

My invention consists in the novel features hereinafter described, reference being had to the accompanying drawing which illustrates an embodiment of my improved packing, selected by me for purposes of illustration, and further illustrates the process by which it is made, and the said invention is fully disclosed in the following description and claims.

In the manufacture of packing for stuffing boxes and other purposes, it has been customary to form a core of asbestos or other suitable material and to cover the same with an exterior casing which has been applied to the core in several different ways. For example, it has been proposed to form a cover by wrapping a sheet of woven or other textile fabric around the core and secure the overlapping edges thereof longitudinally of the packing strip by a suitable adhesive material or otherwise; it has also been proposed to form the casing of braided material in which the strands of the braided fabric extend diagonally with respect to each other; and it has also been proposed to form a woven tube separate and apart from the core and to draw the core through the tube.

All these forms of packing are subject to objections which it is the aim of the present invention to overcome. In the use of the packing having the fabric casing with overlapping edges, the bending of the packing into ring form and especially the expansion of the core due to moisture or wear, causes the casing to open or split along the overlapped edges. In the case of the packing provided with braided covering, the core is not properly confined owing to the fact that a braid is of indeterminable diameter varying under longitudinal and transverse strain, and in the case of a packing in which the core is inserted in a previously formed woven tube, the tube must of necessity be

sufficiently larger than the core to permit the core to be drawn in, and the resulting packing is flimsy and liable to transverse distortion. These difficulties and objections are entirely overcome by my invention, in accordance with which an inclosing casing of practically non-expansile fabric is directly woven upon a compressible core, the warp threads of the casing fabric extending longitudinally of the core and entirely surrounding the same, and the wefts lying in coils extending continuously around the core, interwoven with the warps, and drawn tightly upon the core at the time of interweaving them with the warps, so that the casing is formed directly upon the core and binds it firmly so that practically little or no distortion of the resulting packing can occur, and the swelling of the core by the absorption of oils or other liquids is practically prevented.

In the drawing forming part of this specification, Figure 1 represents an elevation of a portion of the compressible core with the non-expansile woven casing applied to part of the same, portions of the warp and weft threads being shown beyond the confines of the fabric, to illustrate the manner in which the fabric is formed upon the core. Fig. 2 represents a transverse sectional view of my improved packing. Fig. 3 is a longitudinal sectional view of the same.

In carrying out my invention, I first form a compressible core. This may be formed in various ways. I prefer however to form it as shown in Fig. 2 by first preparing a series of laps or layers of woven fabric preferably asbestos cloth 1, which may be folded longitudinally back and forth upon itself, or folded longitudinally into a spiral roll, as shown in Fig. 2 of the drawing, or the core may be formed in any other way which will produce a substantial body of compressible material or fabric of the required cross section. I also prefer to combine with the plies of the fabric 1, as a part of the compressible core, a longitudinally extending portion of rubber 2, preferably in one piece or strip, which applied to the roll or plies of fabric, will produce the desired cross sectional area of the core. I find it convenient in practice to treat the fabric 1 with an adhesive material which will temporarily unite the plies or folds and to adhesively unite the rubber

strip 2 to the exterior ply or layer of the fabric 1 for the same purpose and to preliminarily press the core by means of rollers or dies or in any other desired manner to give it a square, round, or other uniform cross section. For the adhesive material, I also prefer to use what I term a self-vulcanizing rubber composition, that is to say, a liquid or semi-liquid rubber compound which will tend to vulcanize by virtue of the heat to which the packing is always exposed in the stuffing box or other location in which it is used, but I do not limit myself to this particular adhesive.

15 The core having been formed in the manner described I apply thereto an integral substantially non-expansible casing which is formed directly upon the core, ordinarily beginning at one end and progressing gradually to the other. This casing comprises a series of warp threads indicated at 3 in the drawing, disposed longitudinally with respect to the core and entirely surrounding the same, and one, two or more weft threads, 25 indicated at 4 in the drawing, which are disposed substantially transversely with respect to the warp threads and lie in continuous coils around the core, and are interwoven with the warp threads, and simultaneously drawn tightly around and upon the core so as to form a tight inclosing casing which confines the core tightly within the same and prevents any movement of the core within the casing beyond that necessitated in bending the completed packing into 35 circular form to place it in a stuffing box or other location in which it is used.

The weaving operation may be performed in any desired or convenient manner. I prefer to perform it on what is known as a circular loom, by feeding the prepared compressible core centrally through the loom, and preferably through a loom having its circular shuttle course of such diameter that 45 the weft thread or threads will be tightly drawn around and upon the core throughout the entire length of the packing. The finished packing is indicated at 5 in Fig. 1 and in section in Fig. 2.

50 I prefer to form the casing of warp and weft threads made of asbestos having the necessary tensile strength so that the weft threads can be tightly drawn around and upon the compressible core as they are interwoven with the warp threads, thereby compressing the core to a greater or less extent as desired, according to the requirements of the packing. Thus, if a very hard packing is required, the weft threads will be drawn 55 more tightly and made to compress the core to a greater extent than in the case of a comparatively softer packing, in which the weft threads may simply be drawn tight enough to firmly grasp and confine the core. In 60 any case, however, it will be readily under-

stood that in my improved packing, the casing grips and confines the core and gives to the packing a firmness and solidity which is extremely desirable. It will also be seen that as the casing is non-expansible to all intents and purposes, the absorption of liquid by the absorbent portion of the core can have no effect of changing the diameter of the packing or bursting or injuring the integral inclosing casing. At the same time it will be understood that my improved packing may be compressed in a gland or otherwise so as to increase its diameter in a direction perpendicular to the line of pressure and make a tight joint.

I prefer, after the integral non-expansible casing is woven tightly upon the core, to give the packing a final shaping by means of a suitable mold or rollers, or otherwise, especially where a substantially rectangular cross section is desired, although this is not essential. It will also be understood that my improved packing may be saturated with lubricating or other liquid at the time of its manufacture or at any other time without causing the swelling or distortion of the packing or bursting of or injury to the inclosing integral casing. The packing is preferably made in lengths which are rolled or coiled or otherwise prepared for shipment, and in use is formed into rings or gaskets or coils and used in stuffing boxes or other locations where a packing is desired and is made in different diameters and cross sections, according to the uses for which it is particularly designed. I also prefer to impregnate the casing with a vulcanizing adhesive material, as for example, a vulcanizable rubber solution, which may be applied to the warp and weft threads before or at the time of weaving them, or it may be applied to the casing after the same is completed. This treatment of the casing assists in retaining the cross sectional form of the packing and also in retaining the lubricating liquid or material with which the packing or particularly the absorbent core portion thereof is charged.

In packing made in accordance with my improved process and embodying my invention, the warp and weft threads of the casing are practically embedded or impressed into the exterior surfaces of the compressible core to a certain extent. This is due in whole or in part to the formation of the integral casing directly upon the core and drawing the weft threads tightly thereon, which tends to impress both the weft threads and the warp threads into the compressible core and this interlocking of the core with the casing is accentuated by the subsequent shaping operation, in which the completed packing is or may be forced into its final cross sectional form. In any event, the tight grip of the casing upon the core produces a

close interlocking of the warp and weft threads of the casing with the core and makes a more homogeneous packing than could otherwise be produced. The interlocking engagement of the core and casing also tends to prevent the core from slipping or moving with respect to the casing, and in bending the packing into ring or spiral form, there is practically no elongation at 10 the outer circumferential portions of the casing or core, while a slight compressing takes place adjacent to the inner circumferential portions of the casing and the core. Therefore, in bending the packing, it 15 tends to become more substantial rather than less substantial or attenuated, and this increases the effectiveness of the packing.

What I claim and desire to secure by Letters Patent is:—

20 1. The herein described process of making packing, which consists in forming a compressible core, applying thereto a plurality of warps disposed longitudinally of and entirely surrounding the core, and interweaving with said warps, weft coils extending continuously around the core substantially perpendicular to the warps, and drawing said weft coils tightly around the core at the time of interweaving each coil 25 of the same with the warps, to form a non-stretching seamless woven inclosing casing tightly embracing said core.

2. The herein described process of making packing, which consists in forming a compressible core of superimposed layers of fabric, adhesively united, adhesively applying a rubber cushion member thereto, and then applying longitudinal warps entirely around the composite core, and interweaving 30 with said warps, weft coils extending continuously around the core and substantially perpendicular to the warps, and drawing said weft coils tightly around the core to form a seamless non-stretching inclosing 35 casing upon the core.

3. The herein described process of making packing, which consists in forming a compressible core and weaving directly thereon a seamless inclosing casing, by applying a plurality of longitudinally extending warps entirely around the core and

transversely disposed continuous weft coils, substantially perpendicular to the said warp and weft coils being impregnated with vulcanizable material, and drawing said 55 weft coils tightly around the core as they are interwoven with said warps.

4. As a new article of manufacture, a packing consisting of a core comprising a plurality of plies of asbestos fabric, and a 60 rubber cushion member united thereto, and an inclosing seamless non-stretching woven casing consisting of longitudinally extending asbestos warps entirely surrounding said core and transversely disposed asbestos weft 65 coils extending continuously around the core and interwoven with said warps, each weft coil being tightly drawn upon and embracing the inclosed core.

5. As a new article of manufacture, a 70 packing consisting of a core comprising a plurality of plies of asbestos fabric and a rubber cushion member united thereto, and an inclosing seamless non-stretching woven casing consisting of longitudinally extending asbestos warps, entirely surrounding said core and transversely disposed asbestos weft coils extending continuously around the core and interwoven with said warps, each weft coil being tightly drawn upon 75 and embracing the inclosed core, said warps and weft coils being impregnated with vulcanizable adhesive material.

6. As a new article of manufacture, a 80 packing for stuffing boxes and the like, consisting of a compressible core, and a seamless substantially non-stretching woven casing surrounding the same, consisting of longitudinally extending warps and continuous weft coils interwoven therewith, the 85 warps and weft coils being embedded in the exterior surface portion of the compressible core, and interlocked therewith, and held in such interlocked relation with the core by 90 said weft coils.

95

In testimony whereof I affix my signature, in the presence of two witnesses.
